1

This invention relates to air-cooled absorption refrigerating apparatus of the inert gas type, especially apparatus which is adapted for domestic or household use, and has for its object to provide an improvement to simplify the condenser system of such apparatus to obtain greater latitude in mounting and positioning the apparatus in a refrigerator cabinet.

Whereas in compressor-operated refrigerating apparatus a great latitude in the choice of the condenser construction is afforded, certain factors require consideration in the construction of the condenser for an absorption refrigerating apparatus of the inert gas type. In such apparatus relatively small driving forces are developed to effect liquid circulation and cause inert gas circulation. Even a very small increase in pressure in any part of the apparatus may wholly change the different liquid levels therein to such an extent that suitable liquid circulation cannot be effected. Such differences in pressure would easily arise if the resistance to flow of the boiler vapours were increased. Additionally, the presence of the inert gas also presents special problems in the construction of the condenser.

With regard to these factors, one single pipe coil heretofore has generally been used for the condenser of the apparatus and in certain instances a plurality of such pipe coils connected in series. In such arrangements a venting conduit has been provided for the inert gas which extends from the upper part of the condenser, or the conduit for delivering refrigerant condensate has been employed so that both liquid and gas unobstructedly pass therethrough. Further, it has been proposed to provide condensers of the kind heretofore employed in which the outer surface of the pipe coil alone provides adequate heat dissipating surface to reject and give up heat of condensation to air flowing in contact therewith. However, in practice it has not been possible, at least in apparatus adapted for household or domestic use, to employ a pipe coil having adequate heat dissipating surface for air cooling and present relatively small resistance to flow of boiler vapours therein. Accordingly, it has heretofore been necessary to arrange cooling fins on the condenser pipes. The long interconnected condenser pipes in the form of coils, in order to operate in a satisfactory way, requires positioning the apparatus in such manner that blocking of the condenser by liquid condensate therein is avoided. The longer the condenser pipe and the less the cross-sectional area of the passage of the pipe employed, the more this problem must be

2

taken into consideration. In accordance with the invention the foregoing problems are overcome by providing a condenser for absorption refrigerating apparatus of the inert gas type which is constructed in such manner that a plurality of paths of flow are formed for boiler or refrigerant vapours which are connected in parallel and to which a vent conduit is connected to a region at an upper part of such paths of flow, and supplying the boiler or refrigerant vapours to the condenser so that a column of such vapours is effectively utilized to produce a driving force and promote circulation of the vapours in the parallel paths of flow.

15 The invention, together with the above and other objects and advantages thereof, will be more fully understood upon reference to the following description and accompanying drawings forming a part of this specification, and of which:

20 Fig. 1 is a view more or less diagrammatically illustrating a condenser embodying the invention for use in an absorption refrigerating apparatus of the inert gas type;

Fig. 2 diagrammatically illustrates such absorption refrigerating apparatus of the inert gas type;

25 Figs. 3 to 6 illustrate further embodiments of condensers in accord with the invention which are formed of pipe coils;

30 Fig. 7 is a perspective view illustrating a still further embodiment of a condenser in accord with the invention which is formed of plate-like members; and

35 Figs. 8 and 9 are side and top plan views, respectively, of the condenser shown in Fig. 7.

Fig. 1 shows a condenser having conduits for connection in absorption refrigeration apparatus employing inert gas and of a type like that illustrated in Fig. 2. The condenser comprises two end headers or collector pipes 10 and 11, both ends of the former being closed. Both collector pipes are interconnected with a number of essentially parallel condenser pipes 12, which preferably have a cross-sectional area less than that of the collector pipes. As shown, the pipe system described is step-like in form and is intended to be mounted in the rear compartment of a household refrigerator cabinet and adapted to be cooled by air, the natural draft circulation of which is 40 partly due to heat rejected from the absorber of the refrigerating apparatus also disposed in the flue formed at the rear apparatus compartment. In the following description such a system will be designated a "pipe group" in a structural element in condenser systems of large size. Refrig-

erant vapours expelled from the boiler or vapour expulsion unit of the apparatus, like the boiler 20 in Fig. 1, for example, are supplied to the collector pipe 10 through a conduit 21, which is connected between the two uppermost condenser pipes 12. The condensate formed in the pipe system flows from the collector pipe 11, towards which the condenser pipes 12 suitably may incline, through a conduit 14 which is shaped to form a liquid trap and is connected to the evaporator of the refrigerating apparatus, like the evaporator 27 in Fig. 1, for example. By providing the U-trap in conduit 14 the condenser is separated from the gas circulating system of the apparatus. However, in order to permit inert gas to vent from the condenser system the upper part of the collector pipe 11 is connected to a vent pipe 15, which communicates with the gas circulating system of the refrigerating apparatus, as at the gas heat exchanger. Such a vent connection from a condenser to the gas circuit is indicated at 15 in Fig. 2, for example.

When the apparatus is initially started, the condenser mainly contains inert gas, such as hydrogen gas, which prevents condensation of the penetrating refrigerant vapours. The density of such vapours, such as ammonia vapour for example, is greater than that of the hydrogen gas, and consequently the greater part of the condenser is filled upwardly from the bottom thereof with ammonia vapour, while the hydrogen gas will be gradually forced out from one condenser pipe after another, being finally forced upwardly through the pipe 11 and the vent pipe 15. However, all of the condenser pipes need not necessarily be filled with ammonia vapour at such a high pressure that condensation will take place. If the cooling of the condenser is good, it is possible that such a large part of the vapour quantity may condense in the lowest three pipes so that the partial pressure of the refrigerant vapour in the upper condenser pipes will not be sufficiently high for condensation to take place therein. In such case the upper condenser pipes still remain filled with hydrogen gas and act to a certain extent as a pressure equalizing vessel. In the arm A of the end header or collector 10, which is filled with the heavier ammonia vapour, a driving force is produced which causes circulation of such vapour when some of the condenser pipes are filled with hydrogen gas and the vapour in an uncondensed state or vapour phase tends to seek a path of flow leading to the vent pipe 15. This circulation of vapour gradually brings into operation the requisite number of condenser pipes for proper functioning of the condenser.

In Fig. 2 is illustrated absorption refrigerating apparatus of the inert gas type. Such apparatus, which is well known, includes the boiler 20 in which refrigerant vapours are expelled and through a vapour conduit 21 supplied to the condenser system 22. The liquid circulating pump of the apparatus is denoted by 23, its air-cooled absorber by 24 and its absorber vessel by 25. The absorber and the absorber vessel communicate in a well known manner through a liquid heat exchanger 26 with the boiler 20 and the liquid circulating pump 23, respectively. The evaporator of the apparatus is denoted by 27 and its gas heat exchanger by 28. These parts of apparatus form, together with the absorber and the absorber vessel, the gas circulating system of the apparatus, which is built up in a well known manner.

In Fig. 2 the condenser system 22 includes two pipe coils 30 and 31, disposed in two parallel vertical planes. The upper part of the coil 30 is connected to the vapour conduit 21, while the upper part of the coil 31 is connected to the pressure equalizing vessel of the apparatus, denoted by 32, for which vessel the coil 31 at the same time serves as a drain conduit for condensate which may be formed therein. The pressure equalizing vessel is connected by the vent conduit 15 to the gas circulating system of the apparatus. The lower ends of both the pipe coils 30 and 31 are connected to a common conduit 34, through which refrigerant condensate is fed to the evaporator 27. The conduit 34 is arranged in heat exchange relation with the conduit 36, through which the inert gas flowing to the absorber is conducted from the evaporator 21. It is to be understood that the condenser system of Fig. 1 and described above may be connected in absorption refrigeration apparatus of the kind shown in Fig. 2.

Figs. 3 and 4 show further embodiments of the condenser system according to the invention. The arrangement according to Fig. 3 comprises two pipe groups coupled together and of the type shown in Fig. 1, both pipe groups suitably being of the same dimensions and connected by a conduit 40. The reference characters correspond to those of Figs. 1 and 2. The boiler vapours hence flow from the conduit 21 into the first pipe group, which is denoted by 41, whereby the gas forced through the conduit 40 is transferred to the lowest part of the pipe group 42 and through its left-hand end header or collector pipe to the pressure equalizing vessel 32. Both right-hand arms or end headers of the pipe groups are connected to a conduit 43 through which refrigerant condensate is conducted through the liquid trap 14 to the evaporator of the apparatus.

Fig. 4 shows a condenser system comprising three pipe groups according to Fig. 1. The vapour conduit 21 is connected to the left end header or arm of each of the three pipe groups 41, 42 and 44 at points which are located between the two uppermost horizontal pipes of each pipe group. The upper ends of the left-hand end headers or vertical pipes of the pipe groups are mutually interconnected by the conduit 45. The inert gas is forced out from one system after the other and is vented through the upper pipe of the pipe group 44 to the vent conduit 15. The difference in density in the left and right stand-pipes or risers of the pipe groups, described in connection with Fig. 1, will then bring about the successive forcing out of the inert gas from one group after another.

Figs. 5 and 6 show further embodiments of the condenser system according to the invention and differ from the earlier embodiments essentially in that the pipe groups are placed in different horizontal planes parallel to another. The reference characters correspond to those of the preceding figures. The connection of the pipe groups is believed to be sufficiently clear in the drawings. As shown in Fig. 5, the different pipe groups are connected to a common outlet conduit 46 for condensate, which is conducted through a container 47 and the liquid trap 14 to the evaporator. The system is arranged in such a manner that a certain inclination towards the connecting points for the conduit 46 will be obtained and at the same time a rise toward the venting conduit 15 is brought about. Likewise

it is suitable to arrange the horizontal pipe distances in such manner that they are disposed in a greater number of planes than the number of pipes in each pipe group. When the smaller parallel pipes are inclined toward the condensate discharge region 46 and the larger collector pipes or end headers at the discharge side are also arranged to incline toward the same region 46, a condenser arrangement may be formed with a great number of pipes without any danger of liquid blocking due to incorrect positioning or mounting of the apparatus.

By arranging the condenser pipes or the pipe groups, respectively, in the manner described above, it is possible, without any danger of liquid blocking, to select pipes of small internal diameter in such number and with such a large external jacket or heat dissipating surface that the condenser will function properly with air-cooling and yet not require additional heat dissipating fins or similar members. In those cases when for some reason or other it is desired to limit the total pipe length of the condenser, heat dissipating fins or the like may, of course, be employed in a well known manner. It is desirable in such case to arrange the fins so that the upwardly flowing air stream passing from the lower located absorber of the refrigerating apparatus will pass in intimate contact with the fins in the fin packet and will be directed through the central part thereof. This is accomplished by arranging the condenser pipes in the packet so that pipes will be disposed over a greater part of the horizontal cross-section of the air flue.

The invention may be further developed in such manner that the pipe groups are replaced by flat hollow structures welded from sheet metal members, as diagrammatically shown in Figs. 7, 8 and 9. Fig. 7 shows a condenser system comprising three similar flat hollow structures 50, the upper parts of which are connected by conduits 51 and 52. The supply conduit for refrigerant vapours is denoted by 21 and the discharge conduit for refrigerant condensate by 14. In order to couple the hollow structures 50 together it may be suitable to form the structures in the manner shown in Fig. 8. Fig. 9 shows a condenser system built up of members like that shown in Fig. 8. As shown, the hollow structures 50 are formed of pressed plates which preferably are congruent with respect to one another and welded together in pairs along their edges and which in other respects are shaped and joined together in a well known manner in the manufacture of heat-radiators. Due to the high pressure generally prevailing in the apparatus, which pressure may exceed 20 atmospheres, the opposing plates of each hollow structure 50 are united together not only along their edges but also at a number of welded points 55. At these points the plates before being welded together are impressed in such a way that, when the plates are placed together with the concave sides against each other, the convex surfaces of the impressions will lie in pairs against each other. Thereafter the plates of each hollow structure are united together by electrical resistance welding. In order to facilitate the mounting of the hollow structures 50 the connecting openings are arranged in ears 56, which then, as will be clear from Fig. 9, will be placed close to each other, thus forming through conduits 57 to which the interconnecting conduits of the apparatus are coupled. By connecting the vapour conduit 21 from the boiler to the upper ends of the flat hol-

low structures 50, as shown in Fig. 7, a flow within the system will be effected, which causes an equalization of the loading of the condenser due to the hydrogen gas being gradually forced out through the vent conduit.

In view of the foregoing it will now be understood that in the different embodiments illustrated and described above refrigerant vapour is introduced into an end header or a collector of a condenser unit to form a column of such vapour which is effectively utilized as a driving force to promote circulation of refrigerant vapour in a plurality of horizontally extending passages connected at their ends to the vertically extending end headers. Each end header independently of the other end header serves to establish fluid communication between all of the horizontally extending passages embodied in each condenser unit or section and connected thereto.

In Figs. 1, 3, 4 and 5 the conduit 21 for conducting refrigerant vapour from the boiler or vapour expulsion unit is connected at a region of the end collector which is located between the highest and next highest horizontally extending pipes or pipe elements forming the passageways. In the different embodiments the horizontally extending passages or pipes are distributed in a vertical range between a low and higher level and disposed at three or more different levels. Hence, refrigerant vapour is introduced into a vertically extending passage or end header at a region which is above the connection thereto of at least two or more pipes at different levels and above at least half of the different levels at which the horizontally extending passages or pipe elements are disposed.

The invention is not to be limited to the embodiments shown but may be varied in several ways within the scope of the basic inventive idea. It is essential for the condenser system to be vented from a region thereof located sufficiently high within the system so that no hydrogen gas worth mentioning will collect above such region. Further, the condenser system desirably should be mounted in such manner that, due to the difference in density of inert gas and refrigerant vapour, an internal circulation will be established and an increasingly greater part of the condenser will be made available to function and liquefy refrigerant vapour by displacing hydrogen gas through the vent conduit.

Reference is made to applicant's divisional application Serial No. 210,908, filed February 14, 1951, which claims features of the absorption refrigeration apparatus disclosed in Figs. 7, 8 and 9.

I claim:

1. In air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising condenser structure including first and second vertically disposed conduits in spaced apart relation, a plurality of horizontally extending pipes arranged at least at three different levels, each of said pipes having one end thereof connected to said first conduit and the opposite end thereof connected to said second conduit, the cross-sectional areas of said conduits being greater than the cross-sectional areas of said pipes and forming vertical end headers, said first conduit constituting means for establishing fluid communication between all

of said pipes which are embodied in said condenser structure and connected thereto, said second conduit constituting means for establishing fluid communication between all of said pipes which are embodied in said condenser structure and connected thereto, conduit means for conducting refrigerant vapor from the vapor expulsion unit to an end header of said condenser structure at a level which is above the connection thereto of the lowest pipe and below the connection thereto of the highest pipe, conduit means communicating with an end header of said condenser structure for conducting liquid refrigerant therefrom to the evaporator structure, and conduit means communicating with an upper part of said condenser structure for venting inert gas therefrom to the gas circuit.

2. In air-cooled absorption refrigeration apparatus employing hydrogen as an inert gas and ammonia as a refrigerant, a gas circuit including evaporator structure, and a vapor expulsion unit for producing refrigerant vapor, means for supplying liquid refrigerant to the evaporator structure comprising condenser structure including first and second vertically disposed conduits in spaced apart relation, a plurality of horizontally extending pipes arranged at least at three different levels, each of said pipes having one end connected to said first conduit and the opposite end connected to said second conduit, the cross-sectional areas of said conduits being greater than the cross-sectional areas of said pipes and forming vertical end headers, said first conduit constituting means for establishing fluid communication between all of said pipes which are embodied in said condenser structure and connected thereto, said second conduit constituting means for establishing fluid communication between all of said pipes which are embodied in said condenser structure and connected thereto, conduit means for delivering refrigerant vapor from the vapor expulsion unit to said first conduit at a region between the connections thereto of said pipe at the highest level and the pipe at the next highest level, conduit means communicating with the lower end of said second conduit for conducting liquid refrigerant therefrom to the evaporator structure, all of said pipes being inclined to drain liquid therefrom by gravity to said second conduit, and conduit means communicating with an upper part of said condenser structure for venting inert gas therefrom to the gas circuit.

3. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising condenser structure including first and second vertically disposed conduits in spaced apart relation, a group of horizontally extending pipes distributed vertically in the space between said conduits, each pipe having one end connected to said first conduit and the opposite end connected to said second conduit, said conduits being of greater diameter than said pipes and forming vertical end headers, each of said conduits constituting independent means for establishing fluid communication between all of said pipes which are embodied in said condenser structure and connected thereto, conduit means for conducting refrigerant vapor from the vapor expulsion unit to an end header of said condenser structure at a region which is above the connection thereto of at least two or

more pipes at different levels, conduit means communicating with an end header of said condenser structure for conducting liquid refrigerant therefrom to the evaporator, and conduit means communicating with an upper part of said condenser structure for venting inert gas therefrom to the gas circuit.

4. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising condenser structure including first and second vertically disposed conduits in spaced apart relation, a group of horizontally extending pipe elements between said conduits which are disposed at three or more different levels, all of said pipe elements at one end of the group being connected to said first conduit and at the opposite end thereof being connected to said second conduit, each of said first and second conduits forming a vertical end header which constitutes means for establishing fluid communication between all of said pipe elements which are embodied in said condenser structure and connected thereto, conduit means for delivering refrigerant vapor from the vapor expulsion unit to an end header of said condenser structure at a region which is above at least half of the different levels at which said pipe elements are disposed, conduit means communicating with an end header of said condenser structure for conducting liquid refrigerant therefrom to the evaporator structure, and conduit means communicating with an upper part of said condenser structure for venting inert gas therefrom to the gas circuit.

5. In air-cooled absorption refrigeration apparatus containing an inert gas and a refrigerant which in vapor phase is denser than the gas, a gas circuit including evaporator structure, and a vapor expulsion unit for producing refrigerant vapor, means for supplying liquid refrigerant to the evaporator structure comprising a condenser unit including structure providing vertically extending passages forming end headers which are in spaced apart relation and also providing a group of horizontally extending passageways which are distributed in a vertical range and positioned at three or more different levels, one of said end headers being connected to one end of said horizontally extending passages and the other end header being connected to the opposite end of such passages, each of said end headers constituting independent means for establishing fluid communication between all of the horizontally extending passageways embodied in said condenser unit and connected thereto, conduit means for conducting refrigerant vapor from the vapor expulsion unit to said one end header at a region which is above at least half of the different levels at which said horizontally extending passageways are disposed, conduit means communicating with said other end header for conducting liquid refrigerant therefrom to the evaporator structure, and conduit means communicating with the upper part of said condenser unit for venting inert gas therefrom to the gas circuit.

6. In air-cooled absorption refrigeration apparatus containing an inert gas and a refrigerant which in vapor phase is denser than the gas, a gas circuit including evaporator structure, and a vapor expulsion unit for producing refrigerant

vapor, means for supplying liquid refrigerant to the evaporator structure comprising condenser structure including a group of horizontally extending pipe elements distributed in a vertical range disposed between a low level and a higher level and having pipes positioned at three or more different levels, first conduit means for connecting all of said pipe elements at one end of said group and establishing fluid communication at such one end of all of said pipe elements which are embodied in said condenser structure, second conduit means for connecting all of said pipe elements at the opposite end of said group and establishing fluid communication at such opposite end of all of said pipe elements which are embodied in said condenser structure, third conduit means for delivering refrigerant vapor from the vapor expulsion unit to said first conduit means at a region thereof which is above and below the pipe elements disposed at said low and higher levels, respectively, fourth conduit means communicating with said second conduit means for conducting liquid refrigerant therefrom to the evaporator structure, and conduit means communicating with an upper part of said condenser structure for venting inert gas therefrom to the gas circuit.

7. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising condenser structure including a group of horizontally extending pipe elements distributed at three or more different levels in a vertical range disposed between a low level and a higher level, first conduit means for connecting all of said pipe elements at one end of the group and establishing fluid communication at such one end of all of said pipe elements which are embodied in said condenser structure, second conduit means for connecting all of said pipe elements at the opposite end of the group and establishing fluid communication at such opposite end of all of said pipe elements which are embodied in said condenser structure, third conduit means for delivering refrigerant vapor from the vapor expulsion unit to said first conduit means at a region which is above at least half of the different levels at which said pipe elements are distributed, fourth conduit means communicating with said second conduit means for conducting liquid refrigerant therefrom to the evaporator structure, and conduit means communicating with an upper part of said condenser structure for venting inert gas therefrom to the gas circuit.

8. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising a plurality of condenser sections, each of said sections including first and second vertically disposed conduits in spaced apart relation and a plurality of horizontally extending pipes arranged at least at three different levels, each of said pipes having one end connected to said first conduit and the opposite end connected to said second conduit, the cross-sectional areas of said conduits being greater

than the cross-sectional areas of said pipes and forming end headers, said first conduit constituting means for establishing fluid communication between all of said pipes which are embodied in the condenser section and connected thereto, said second conduit constituting means for establishing fluid communication between all of said pipes which are embodied in the condenser section and connected thereto, conduit means for conducting refrigerant vapor from the vapor expulsion unit to the end headers of a plurality of said condenser sections at regions which are above the connection of the lowest pipe to each such end header and below the connection of the highest pipe to each such end header, conduit means communicating with an end header of each such condenser section for conducting liquid refrigerant therefrom to the evaporator structure, and conduit means communicating with an upper part of each such condenser section for venting inert gas therefrom to the gas circuit.

9. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising first and second condenser sections, each of said sections including first and second vertically disposed conduits in spaced apart relation and a plurality of horizontally extending pipes arranged at least at three different levels, each of said pipes having one end connected to said first conduit and the opposite end connected to said second conduit, the cross-sectional areas of said conduits being greater than the cross-sectional areas of said pipes and forming end headers, said first conduit constituting means for establishing fluid communication between all of said pipes which are embodied in the condenser section and connected thereto, said second conduit constituting means for establishing fluid communication between all of said pipes which are embodied in the condenser section and connected thereto, conduit means for conducting refrigerant vapor from the vapor expulsion unit to an end header of the first condenser section at a region which is above the connection of the lowest pipe thereto and below the connection of the highest pipe thereto, conduit means connecting an upper part of said first condenser section and an end header of said second condenser section, conduit means communicating with an end header of each condenser section for conducting liquid refrigerant therefrom to the evaporator structure, and conduit means communicating with an upper part of said second condenser section for venting inert gas therefrom to the gas circuit.

10. In air-cooled absorption refrigeration apparatus employing hydrogen as an inert gas and ammonia as a refrigerant, a gas circuit including evaporator structure, and a vapor expulsion unit for producing refrigerant vapor, means for supplying liquid refrigerant to the evaporator structure comprising a plurality of condenser sections, each of said sections including first and second vertically disposed conduits in spaced apart relation, a plurality of horizontally extending pipes arranged at least at three different levels, each of said pipes having one end connected to said first conduit and the opposite end connected to said second conduit, the cross-sectional areas of said conduits being greater than the cross-

tional areas of said pipes and forming vertical end headers, said first conduit constituting means for establishing fluid communication between all of said pipes which are embodied in the condenser section and connected thereto, said second conduit constituting means for establishing fluid communication between all of said pipes which are embodied in the condenser section and connected thereto, conduit means for conducting refrigerant vapor from the vapor expulsion unit to the first conduits of a plurality of said condenser sections at regions between the connections to each such first conduit of said pipe at the highest level and the pipe at the next highest level, conduit means communicating with the lower ends of the second conduits of each such condenser section for conducting liquid refrigerant therefrom to the evaporator structure, all of said pipes being inclined downwardly to drain liquid therefrom by gravity to the second conduits of said sections, and conduit means communicating with an upper part of each such condenser section for venting inert gas therefrom to the gas circuit.

11. In an air-cooled absorption refrigeration apparatus employing hydrogen as an inert gas and ammonia as a refrigerant, a gas circuit including evaporator structure, and a vapor expulsion unit for producing refrigerant vapor, means for supplying liquid refrigerant to the evaporator structure comprising first and second condenser sections, each of said sections including first and second vertically disposed conduits in spaced apart relation, a plurality of horizontally extending pipes arranged at least at three different levels, each of said pipes having one end connected to said first conduit and the opposite end connected to said second conduit, the cross-sectional areas of said conduits being greater than the cross-sectional areas of said pipes and forming vertical end headers, said first conduit constituting means for establishing fluid communication between all of said pipes which are embodied in the condenser section and connected thereto, said second conduit constituting means for establishing fluid communication between all of said pipes which are embodied in the condenser section and connected thereto, conduit means for conducting refrigerant vapor from the vapor expulsion unit to the first conduit of said first condenser section at a region between the connections thereto of the pipe at the highest level and the pipe at the next highest level, conduit means connecting the upper end of the second conduit of said first condenser section and the lower end of the first conduit of said second condenser section, conduit means communicating with the lower ends of the second conduits of said first and second condenser sections for conducting liquid refrigerant therefrom to the evaporator structure, all of said pipes being inclined downwardly to drain liquid therefrom by gravity to the second conduits, and conduit means communicating with an upper part of said second condenser section for venting inert gas therefrom to the gas circuit.

12. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising

a plurality of condenser sections, each section including first and second vertically disposed conduits in spaced apart relation, a group of horizontally extending pipes distributed vertically in the space between said conduits, each pipe having one end connected to said first conduit and the opposite end connected to said second conduit, said conduits being of greater diameter than said pipes and forming vertical end headers, each of said conduits constituting independent means for establishing fluid communication between all of said pipes which are embodied in the condenser section and connected thereto, conduit means for conducting refrigerant vapor from the vapor expulsion unit to the end headers of a plurality of said condenser sections at regions of each such end header which are above the connection thereto of at least two or more pipes at different levels, conduit means communicating with end headers of each such condenser section for conducting liquid refrigerant therefrom to the evaporator structure, and conduit means communicating with an upper part of each such condenser section for venting inert gas therefrom to the gas circuit.

13. In an air-cooled absorption refrigeration apparatus containing an inert gas and refrigerant fluid which in vapor phase is denser than the gas, a gas circuit including evaporator structure, and a vapor expulsion unit for producing refrigerant vapor, means for supplying liquid refrigerant to the evaporator structure comprising first and second condenser sections, each of said sections including first and second vertically disposed conduits in spaced apart relation, a group of horizontally extending pipes distributed vertically in the space between said conduits, each pipe having one end connected to said first conduit and the opposite end connected to said second conduit, said conduits being of greater diameter than said pipes and forming vertical end headers, each of said conduits constituting independent means for establishing fluid communication between all of said pipes which are embodied in the condenser section and connected thereto, conduit means for conducting refrigerant vapor from the vapor expulsion unit to an end header of said first condenser section at a region which is above the connection thereto of at least two or more pipes at different levels, conduit means connecting the upper part of said first condenser section and an end header of said second condenser section, conduit means communicating with end headers of said first and second condenser sections for conducting liquid refrigerant therefrom to the evaporator structure, and conduit means communicating with an upper part of said second condenser section for venting inert gas therefrom to the gas circuit.
